UNITED STATES PATENT OFFICE.

FREDERICK SAMUEL MILLICAN, OF VANCOUVER, BRITISH COLUMBIA, CANADA.

BOAT.

1,038,176.

Specification of Letters Patent. Patented Sept. 10, 1912.

Application filed February 7, 1912. Serial No. 675,964.

To all whom it may concern:

Be it known that I, FREDERICK SAMUEL MILLICAN, of the city of Vancouver, in the Province of British Columbia, Canada, have 5 invented certain new and useful Improvements in Boats, of which the following is the specification.

My invention relates to improvements in boats and the object of the invention is to 10 devise means whereby the deck of the boat may be readily converted into an arena for show purposes with tiers of seats to each side so arranged that the normal width of the boat will not be increased and it consists 15 essentially of seat sections the top of which are provided with seats arranged in gradually ascending tiers, means for moving the seat sections outwardly over the side of the boat from a position centrally of the deck, 20 and means for supporting the seat sections when moved into a position over the side of the boat as hereinafter more particularly explained by the following specification.

Figure 1, is a sectional view through the 25 boat showing my sections in their outer position. Fig. 2, is a similar view to Fig. 1 showing the seat sections in their inner position. Fig. 3 is an enlarged view of one of the seat sections and supports therefor. 30 Fig. 4, is an end view showing the means of operating the sections. Fig. 5, is an enlarged perspective detail showing seat section supports.

In the drawings like letters of reference 35 indicate corresponding parts in each figure.

A is the hull of a boat provided with the usual deck B. Beneath the deck B is located a main driving shaft C driven from any suitable source of power and journaled 40 in suitable bearings. C² is a driving pinion mounted thereon.

C³ is a gear mounted in an arbor C⁴ journaled in bearings C⁵.

D are guides secured to the deck B of the 45 boat and preferably of dovetail form.

E are the seat sections provided with gradually ascending tiers of seats E'.

E² are guide-ways designed to fit over the

guides D and F are ball bearings resting upon the guides D so as to minimize the 50 friction.

H is a rack located beneath the seat sections and with which the gear C³ meshes.

I are swinging brackets secured to the side of the boat and onto which the seat 55 sections are carried.

When I desire to use my device all that is necessary to do is to swing the arms or brackets I into a position at right angles with the side of the boat by means of a suitable cable or otherwise. The shaft C is then driven so as to carry the seat sections onto the supporting brackets thereby leaving the center of the deck free for use as an arena. 60

By this construction it will be seen that I 65 provide a large seating capacity by my movable seat sections which may be carried to the center of the boat when not in use so that the boat does not appear other than an ordinary boat and of no greater width and 70 having as much promenade space as the ordinary deck. The deck cabins of course may be located beneath the seat sections in the same manner as an ordinary cabin is located. 75

What I claim as my invention is.

1. In a boat, sections having tiers of seats arranged on top thereof, means for slidably supporting the seats on the boat deck, means for supporting the sections over the side of 80 the boat, and means for sliding the sections laterally from the boat deck onto the supports located over the side of the boat, as and for the purpose specified.

2. In a boat, sections having tiers of seats 85 arranged on top thereof, guide-ways on the deck for supporting the sections, swinging brackets secured to the side of the boat, and means for sliding the sections across the deck onto the supporting brackets as and 90 for the purpose specified.

FREDERICK SAMUEL MILLICAN.
